(57) **CLAIM**

The ornamental design for a smart phone having foldable display, as shown and described.

DESCRIPTION

FIG. 1 is a front, right perspective view of the smart phone having foldable display showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right perspective view of the smart phone having foldable display in an unfolded state;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a partially enlarged view showing portion "A" in FIG. 6; and,

FIG. 16 is a front, right perspective view of the smart phone having foldable display of FIG. 1 shown with environment. The dot-dot-dash broken line and circle in the FIG. 6 and FIG. 15 views are imaginary lines that are included for reference purposes only to identify the partially enlarged view; the dot-dot-dash lines form no part of the claimed design. The dot-dash broken line in the FIG. 16 view indicates the path along which the pen is inserted and forms no part of the claimed design. The broken lines are directed to environment and form no part of the claimed design.
